INVENTOR:

BYRON PHELPS,

BY
R. Phelps,
ATTORNEY

UNITED STATES PATENT OFFICE.

BYRON PHELPS, OF SEATTLE, WASHINGTON.

DESIGN FOR AN ESCUTCHEON-PLATE.

SPECIFICATION forming part of Design No. 30,113, dated January 31, 1899.

Application filed January 8, 1899. Serial No. 701,050. Term of patent 14 years.

To all whom it may concern:

Be it known that I, BYRON PHELPS, a citizen of the United States, residing at Seattle, county of King, State of Washington, have invented and produced a certain new, useful, and original Design for an Escutcheon-Plate, of which the following is a full, clear, and exact description.

In the accompanying drawing, forming part of this specification, the figure shows my new design.

As shown in the drawing, the leading feature of my design consists of a lengthened rectangular part, having at one side a rectangular projection. Said extended rectangular

part has a circular portion on the body thereof substantially opposite said rectangular projection.

Having described my invention, what I claim as new, and desire to secure by Letters Patent, is—

The design for an escutcheon-plate herein shown and described.

Signed at New Britain, Connecticut, this 29th day of December, 1898.

BYRON PHELPS.
